MOISTENING DEVICE

Robert F. Morrison, Oak Park, Ill., assignor to
Ditto, Incorporated, Chicago, Ill., a corpora-
tion of West Virginia

Application January 15, 1940, Serial No. 313,977

3 Claims. (Cl. 91—51)

This invention relates to moistening devices designed particularly for use in connection with liquid process duplicating machines, in which copy sheets are forwarded into impression relationship with a master sheet carried around by a drum, and in which the means for forwarding the copy sheets to the drum comprises a pair of rollers, to one of which a supply of solvent is fed for application to the face of the copy sheet on its way to the drum. It is the object of this invention to provide a new and improved arrangement of forwarding rollers and cooperating parts by which a film of solvent is applied to a sheet passing between the rollers.

In the construction illustrated, improved means is shown for applying a film of moisture to the lower one of the cooperating forwarding rollers, this arrangement comprising a receptacle for holding a supply of solvent in contact with the moistening roller without the intervention of any spreader or other intermediate roller. In this construction, an improved arrangement of wiper means is provided, comprising wipers of sponge rubber or other suitable absorbent material engaging both side faces of the moistening roller, together with suitable means for pressing such wiper members into operative relation to the moistening roller. An improved arrangement of wiper means for the ends of the moistening roller is also provided, comprising scraper means of rubber bearing directly on the ends of the roller and on the end portions of the cylindrical face of the roller.

It is another object of this invention to improve moistening devices in sundry details hereinafter pointed out. The preferred means by which the several objects have been attained are shown in the accompanying drawing, in which—

Fig. 1 is a vertical sectional view through the preferred form of my improved machine;

Fig. 2 is a horizontal sectional view taken substantially at the line 2—2 of Fig. 1;

Fig. 3 is a vertical sectional view taken substantially at the line 3—3 of Fig. 1; and

Fig. 4 is a horizontal sectional view taken substantially at the line 4—4 of Fig. 3.

Referring now to the several figures of the drawing, in which corresponding parts are indicated by the same reference characters, 19 indicates the drum of a liquid process duplicating machine rotatably mounted in position on a horizontal axis on a framework 20 and arranged for holding a master sheet 22 removably in position on the drum. An impression roller 26 is rotatably mounted in pressure relationship with the drum

so as to cooperate with the drum for carrying a copy sheet forwardly in engagement with the outer face of the master sheet 22.

Means is provided for forwarding copy sheets one at a time to the drum and the impression roller, such means comprising two forwarding rollers 84 and 85 mounted in cooperative relationship to each other at a short distance to the rear of the impression roller 26. The rollers 84 and 85 are designed to be driven at substantially the same surface speed as that of the drum 19, as is usual in machines of this type. The lower roller 85 is mounted for rotation within a tank or receptacle 86 adapted to hold a supply of solvent below and about the roller, such roller 85 being supported by arms or levers 87 of angular formation as is shown in Fig. 1 and pivotally mounted by means of machine screws 88, coiled springs 89 being provided for pressing the roller 85 upwardly into pressure relationship with the roller 84 which is mounted on a fixed axis on the framework.

In the arrangement shown, the roller 84 is provided with a facing of sponge rubber or the like, the lower roller 85 being provided with a comparatively hard facing portion made of comparatively hard rubber or neoprene or other similar material. Means (not shown) is provided for supplying solvent to the receptacle 86, such means being of any suitable type well understood in connection with this type of machine. The receptacle 86 is also preferably provided with overflow means of any suitable type for limiting the depth of the solvent therein.

At opposite sides of the roller 85, wipers 90 and 91 are provided, formed of sponge rubber or the like, with the surface skin removed so as to make the wipers readily absorbent for removing surplus moisture from the roller 85 as the roller revolves. In the arrangement shown, the wiper 90 is mounted in a shoe 92, which is pressed by a set screw 93 toward the roller 85 for adjusting the pressure of the wiper on the roller. The wiper 91, on the other hand, is mounted in a shoe 94 which is pressed by a coiled spring 95 toward the roller for assuring that such wiper 91 shall have effective engagement with said roller. Below the shoes 92 and 94, pins 96 have been provided for supporting the wipers in their operative positions. At opposite ends of the roller 85, at points between the wipers 90 and the roller 84, scrapers 97 have been provided having notches at 98 (see Fig. 12) so as to engage both the end faces of the roller and the end portions of the cylindrical surface of the roller for scrap-

ing surplus solvent from the roller. In the arrangement shown, the scrapers 97 are mounted in holders 99 in the form of channels, such channels being pressed toward the ends of the roller by means of set screws 100 which are adjustable for varying the pressure of the scrapers against the roller.

As the roller 85 rotates, it picks up a supply of solvent from the receptacle 86 for application to the bottom face of the copy sheet going forward to the drum, the wipers 90 and 91 being adapted to limit the amount of liquid supplied to the copy sheet, and the wipers 97 being effective for removing the surplus liquid from the ends of the roller 85.

In the arrangement shown, a table 101 of any suitable type is provided to the rear of the forwarding rollers 84 and 85 for supporting a pile of copy sheets in convenient position for being fed to the forwarding rollers. A cover plate 102 is also provided above the roller 84 for preventing splashing of the solvent upon the master sheet carried by the drum.

While I prefer to employ the form of construction as shown by the drawing and as above described, my invention is not to be limited to such arrangement except so far as the claims may be so limited, it being understood that changes might well be made in the construction and arrangement without departing from the spirit of the invention.

I claim:

1. In a moistening mechanism for applying a film of liquid to a sheet and forwarding such sheet into impression relationship with a master sheet printed in reverse with copying ink, the combination of a roller, means cooperating with said roller for forwarding a sheet in contact with the upper face of the roller, a receptacle adapted to hold a quantity of liquid in contact with the lower portion of said roller for enabling the roller to pick up a supply of liquid for application to the bottom face of the sheet, a wiper member of absorbent material engaging the upwardly moving face portion of said roller for prevent-

ing the application of an excessive amount of the liquid to said sheet, adjustable means for pressing said wiper member with a controlled degree of pressure against said roller, a second wiper member of absorbent material engaging the downwardly moving face portion of said roller, and yielding means for pressing said second wiper member effectively against said roller.

2. In a moistening mechanism for applying a film of liquid to a sheet, the combination of a roller, means cooperating with said roller for forwarding a sheet in contact with the upper face of the roller, a receptacle adapted to hold a quantity of liquid in contact with the lower portion of said roller for enabling the roller to pick up a supply of liquid for application to the bottom face of the sheet, wiper means engaging the upwardly moving face portion of said roller for preventing the application of an excessive amount of liquid to said sheet, and wiper members for the end portions of said roller and notched so as to engage both the end faces and the cylindrical surface of the roller at the upwardly moving face portion thereof for removing surplus liquid therefrom.

3. In a moistening mechanism for applying a film of liquid to a sheet, the combination of a roller, means cooperating with said roller for forwarding a sheet in contact with the upper face of the roller, a receptacle adapted to hold a quantity of liquid in contact with the lower portion of said roller for enabling the roller to pick up a supply of liquid for application to the bottom face of the sheet, wiper means engaging the upwardly moving face portion of said roller for preventing the application of an excessive amount of liquid to said sheet, wiper members for the end portions of said roller and notched so as to engage both the end faces and the cylindrical surface of the roller at the upwardly moving face portion thereof for removing surplus liquid therefrom, and adjustable means for pressing said wiper members into engagement with said roller.

ROBERT F. MORRISON.
